NOVEL OR IMPROVED MEANS FOR USE
MORE ESPECIALLY IN DISPLAYING AND
CHANGING MUSICAL SCORE

Beatrice Norah Carrington, Retford, England

Application December 8, 1943, Serial No. 513,449
In Great Britain November 26, 1942

10 Claims. (Cl. 88—24)

1

The invention relates more especially to musical score used by members of an orchestra, and has for its main object to provide novel or improved means whereby such score may be displayed in an improved manner and changed during the playing of the orchestra. The invention is, however, applicable in other cases where matter under control at a given place is required to be displayed at another or other places.

Describing the invention as applied to displaying musical score it consists in photographic reproduction of the music sheets in miniature (say 2½ inches by 2 inches) to produce transparencies which are set in a frame or number of frames and used, in conjunction with a projector or projectors, to throw images of the score, one by one, on to a suitable screen in view of the respective instrumentalist, who may himself change the image either directly by hand or through the agency of electrical means, or the images of all or some of the projectors may be changed simultaneously from one point by suitable electric connections.

Two embodiments of the invention are described with reference to the accompanying drawings in somewhat diagrammatic form. Of these drawings

Figure 1 is a front elevation partly broken away to illustrate the controlling instrument hereinafter termed the console.

Figure 2 is a longitudinal sectional view the section being taken on the line 2, 2, of Figure 1.

Figure 3 is a fragmentary sectional view the section being taken in the plane indicated by the line 3, 3, of Figure 2.

Figure 4 is a transverse sectional view of the console, the section being taken in the plane indicated by the line 4, 4, of Figure 2.

Figure 5 is a vertical transverse sectional view of one of the displaying units hereinafter referred to as projectors.

Figure 6 is a plan view of the projector shown in Figure 5 but with the top cover removed.

Figure 7 is a fragmentary sectional plan view, the section being taken in the plane indicated by the line 1, 1, of Figure 5.

Figure 8 is a fragmentary sectional plan view the section being taken in the plane indicated by the line 8, 8, of Figure 5.

Figure 9 is a wiring diagram.

Figure 10 is an outside perspective view of the projector shown to a reduced scale.

Figure 11 is a fragmentary plan view showing details of the disc.

Referring first to Figures 1 to 9, the console 20 (shown in Figures 1 to 4) comprises an inner disc

2 or dial 21 and an outer disc or dial 22 each having a set of dialling tabs numbered from 1 to 9 and to 0. The tabs on the inner disc 21 indicate units and the tabs on the outer disc 22 indicate tens. The discs are operated in a manner similar to that employed with dialling on telephones, that is to say the operator places his finger in the desired tab of each disc and in each case brings it round to a stop 23. This movement of each dial sets up electric impulses which are transmitted to the several projectors of which one is shown and indicated by the numeral 24.

In each projector 24 is a number of discs 25 adapted to be turned about a central spindle 26. The discs 25 are turned one at a time by electric impulses transmitted by operation of the inner dialling disc 21. The discs 25 are turnably mounted upon the top of an externally screwed sleeve 27 which is lowered and raised by impulses regulated by the outer dialling disc 22. The discs 25 are apertured to receive transparencies upon which sheets of the score are depicted after the manner of lantern slides.

By raising the discs to bring the appropriate disc to the first or inner focal plane and by turning the said disc to cause the appropriate transparency to come into the rays transmitted by a lamp 65, an enlarged replica of the transparency is projected on to a screen 66 at the top of the projector (see Figure 10).

The means for producing the electric impulses by the discs 21 and 22 of the console will now be described with reference to Figures 1 to 4 and 9: The inner dial 21 is secured on the outer end of a sleeve 28 by means of an inner screwed collar 29 and outer screwed nut 30. Keyed on the sleeve 28 is a wheel 31 shown only in Figure 2 but it is similar to another wheel 32 shown in Figures 2 and 4. The wheel 32 is keyed to a second sleeve 33 turnable on the sleeve 28 and having secured to its outer end the outer dial 22, by means of a nut 34 screwed on the end of the sleeve 33 and pressing the disc 22 up against a shoulder on the sleeve.

The wheel 32 (see Figures 2 and 4) has notches 35 cut in its periphery and with these notches engages a pin 36 carried by a pair of spring arms 37, 37, pivoted at 38 to one of the bolts 39 which secure parts of the casing hereinafter described. Hence, when the wheel 32 is rotated by rotation of the dial 22, it causes the arms 37 to rock and make a succession of contacts with one of two contact members 38, 38 thus successively sending electric impulses to each of the projectors 24. The wheel 32 with the dial 22 is returned to the nor-

mal position (as indicated in Figure 1) by a scroll spring 86 (shown in section only in Figure 2). In order to retain the wheel 32 in the position to which it has been dialled it has integral with it a ratchet wheel 40 (see Figures 2 and 3) engaged by a pawl 41 pivoted to a toothed wheel 42 turnably mounted on the sleeve 33 and this latter is normally held from turning by a detent 43. Thus the wheel 32 can turn in one direction as the pawl 41 can click over the teeth of the wheel 40 but it is held from turning back. The detent 43, however, is carried on an armature 44 which, when attracted by the core of a coil 45, frees the wheel 42 and allows it, together with the wheel 40, wheel 32 and dial 22, to return to their normal positions by the action of the scroll spring 86.

The wheel 31 has notches 46 (see Figure 2) engaged by arms 47 similar to the arms 37 and adapted to engage against contacts 48. Thus when the disc 21 is dialled electric impulses are also sent to the projectors. The wheel 31 is turned against the force of a scroll spring 49; and, to prevent the return of the wheel 31 (and dial 21), a brake wheel 50 is keyed on the end of the sleeve 28 and engages frictionally against a friction disc 51 keyed on an arbor 52 which passes freely through the sleeve 28. The arbor 52 is pressed forwardly by a coil spring 53 to press the disc 51 against the brake wheel 50. The disc 51 is kept from turning by the provision of a square 54 on the end of the arbor 52 engaging in a square hole in a fixed cover plate 55. The forward end of the arbor 52 is provided with a press button 56. The sleeves 28 and 33 are supported in bearings of two partition walls 113 and 114 within the casing of the console. Between the disc 51 and the spring 53 is a pair of spring arms 56a adapted to make contact (when the knob 56 is pressed) with a contact ring 57 which closes another circuit to the projectors. The pressing of the knob 56 presses the disc 51 out of engagement with the brake wheel 50 and so allows the wheel 31 and dial 21 to return to normal.

The details of the projector 24 will now be described. The discs 25 are spaced apart by spacing discs 58 each of which has apertures housing rollers 59 by which one disc 25 is turnably supported from the disc below. The lowermost spacing disc 58 rests upon the head 60 of the hollow double threaded screw 27 which is free for up-and-down movement but is held from turning by a bar 61 the ends of which engage in vertical slots of two brackets 62 carried on a lid 63 of an internal casing 64 within the projector casing. Engaging on the threads of the screw 27 is a nut 68 mounted in ball bearings 69 of the lid 63, and integral with the nut 68 is a wide sleeve 70 which has integral with it a wheel 71 provided with peripheral notches 72 (see especially Figure 7). These notches are engaged by a pawl 73 pivotally mounted on an arm 74 pivoted on the sleeve 70 and supported by a collar 75 thereon. Secured to the outer end of the arm 74 is the curved core 76 (see Figure 7) of a sector-shaped solenoid 77 secured in the casing 64. The core is drawn in, when the solenoid is excited, against the force of a coil spring 77'. The pawl 73 has two teeth 78, 79, the tooth 78 being normally in engagement with one of the notches 72 of the wheel 71 and it is held in engagement by an arm of a double spring 80 engaging on either side of a pin 81 on the core 82 of a solenoid 83 mounted on the arm 74. The core is pressed out by an internal spring (not shown). When the solenoid 83 is excited it draws in the core 82 and reverses the action of

the pawl 73. The solenoid 77 receives impulses from the console as above described corresponding in number to the number on the tab operated on the dial 22. The screwed sleeve 27 is therefore turned to lower the discs 25 until the appropriate disc comes to the inner focal plane, this latter being just in front of a condenser 84 carried by a bracket 85 secured in the projector casing.

10 The spindle 26 already referred to extends up through the sleeve 70, nut 68, screwed sleeve 27 and discs 25 and is journaled in the bottom wall of the projector and in a cover plate 87 which also mounts the projector lens 88. Set in the 15 spindle 26 is a projection 89 and each disc 25 has in its inner periphery a notch 90. The projection 89 lies in the notch 90 of whichever disc 25 lies in the inner focal plane, so that rotation of the spindle 26 will rotate the said disc but none of the others. Those of the discs 25 which are not in the inner focal plane are locked from turning by a guard plate 91 which enters peripheral notches 92 of the discs 25 (see Figure 6) but the guard plate itself has a notch 93 (see Figure 5), so that the disc 25 which lies in the inner focal plane is free to be turned by the spindle 26.

Keyed on the spindle 26 is a wheel 94 having notches 95 (see Figure 8) engaged by a double pawl 96 similar in all respects to the pawl 73 already described, and actuated in the same way 30 by a solenoid 97 and reversed by a solenoid 98. Thus the spindle 26 and the appropriate disc 25 is turned in either direction.

It is important that the disc 22 be dialled before the dialling of the disc 21 for all numbers above 9; because, if in such case the disc 21 were dialled first, the lowermost disc would turn and its notch 90 come out of register with the locking plate 91, thereby preventing the discs 25 being lowered by the screwed sleeve 27 which would cause jamming of the parts and possible injury thereto. In order to prevent this contingency a disc 99 is secured on the lower end of the spindle 26 said disc having a notch 100 (see Figure 9) into which a tooth 101 on a switch arm 102 is adapted to enter when the spindle is in normal position. When so entered the arm 102 engages two contacts 103 and closes the circuit to the solenoid 77. At other positions of the disc 99 the current to the solenoid 77 is cut off.

It will be seen from Figure 6 that there are eleven apertures in each disc, one 104 being a round aperture of sufficient diameter to allow the respective disc to pass down over the tube which carries the condenser 84. Each of the other apertures 105 is adapted to carry a transparency 106 (see Figures 6 and 11) slid into grooves formed in the slides and inner end of each aperture. Opposite each aperture the periphery of each disc may have a half-moon recess 107 to facilitate removal of a transparency from any one of the recesses. Thus there may be ten transparencies in each disc 25.

It will have been noted that there are ten discs 25 so that there may be any number of transparencies up to one hundred.

Assuming that the conductor of the orchestra desired to have transparency No. 67 projected on the screen of each projector, having seen that both dials were in normal positions, he would press tab 6 on the outer dial. In doing this he would cause the arms 37 to contact six times with the right hand pair of two studs 38 allowing current to flow from positive main through 70 a relay coil 139 back to negative main (see Figure 75

9). This will cause the relay 139 to be excited six times and so close an armature 140 against a contact 141 six times and pass current, in six impulses, to the solenoid 77 but passing through the switch arm 102. The solenoid 77 acting through the pawl 13 gives six turning impulses to the wheel 71 in an anti-clockwise direction and the nut 68 turns with it, lowering the screwed sleeve 27 until the sixth disc (from the bottom) comes into the inner focal plane. The said disc is then opposite the notch 93 in the guard plate 91 so that it is no longer locked against turning. During dialling of the disc 22 15 its wheel 40 clicked past the pawl 41. After dialling, it therefore remains in the position dialled, because the wheel 42 carrying the pawl 41 is being held by the detent 43.

Next, 7 is dialled on the inner dial. This rocks the arm 41 seven times into contact with the right hand pair of terminals 48 each time causing excitation of a relay 149. This causes current to flow by seven pulses to the solenoid 97 (see Figure 8) which, through the pawl 96 and wheel 94, turns the spindle 26. The projection 89 on the spindle is now lying in the inner notch of the sixth disc so that it causes that disc only to turn until No. 67 transparency comes into position to be projected on to the screen. The turning of the spindle 26 turns the disc 99 (see Figure 5) and this forces the tooth 101 (see Figure 9) out of the notch 100 and breaks the circuit to the solenoid 77 so that, if the outer disc be inadvertently dialled again, it will have no effect. After dialling the disc 21 is held from returning by the brake device 50, 51.

When it is desired to change a transparency the parts must first be brought back to their normal positions. This is effected simply by pressing the knob 56. This has two main effects: (i) It frees the brake device 50, 51 (see Figure 2) and allows the disc 21 to go back by the action of the scroll spring 49. (ii) It makes contact between the arms 56a and the contact ring 51. This itself has two effects: (a) It causes excitation of the solenoid 45 freeing the wheel 42 thus allowing the wheel 32 and disc 22 to go back under the action of the scroll spring 86. (b) It causes excitation of the two solenoids 83 and 98 with consequent reversal of the two pawls 73 and 96.

The wheels 31 and 32, in going back, again rock the arms 37, 47, so that the solenoids 77, 97, are again excited by impulses. Thus they bring all the discs 25 back to their normal positions. The solenoids 45, 83 and 98 (see Figure 9) are shown as connected in series for the sake of simplicity, but they might, of course, be connected in parallel, if desired.

115 is a fan driven by a motor 116 for cooling the interior of the projector.

In order to operate the discs 25 of each projector by a performer, press buttons may be provided to switch on current to the solenoids 77 and 97 and to the reversing solenoids 83 and 98.

The phrase "set of discs" and the term "disc" as used in the following claims is also to be construed as covering a "pair of drums" and a "drum," respectively.

Having fully described my invention what I claim and desire to secure by Letters Patent is:

1. Means whereby matter under control at a given place may be displayed by a projector or projectors at another place, each projector comprising a set of discs concentrically mounted a set of transparencies arranged on each disc in

5 a circle concentric with the disc with one blank space in the circle through which the light beam can pass, electrically controlled means for moving the set of discs axially to bring any desired one of them into the inner focal plane of the projector, and electrically controlled means for turning such disc only to bring any desired one of its transparencies into the beam of light of the projector.

10 2. Means whereby matter under control at a given place may be displaced by a projector or projectors at another place, each projector comprising a set of discs concentrically mounted a set of transparencies arranged on each disc in a circle concentric with the disc with one blank space in the circle through which the light beam can pass, electrically controlled means for moving the set of discs axially to bring any desired one of them into the inner focal plane of the projector, electrically controlled means for turning such disc only to bring any desired one of its transparencies into the beam of light of the projector, dialing means comprising two discs with numbers thereon, the dialing of each disc causing a number of electric impulses to be transmitted to each projector, and means in each projector affected by the said impulses to move the transparency-carrying discs axially endwise and to turn them by the requisite amount to display the image of the required transparency.

15 3. In combination with the mechanism defined in claim 2, a notched wheel with which each dialing disc is connected, an arm engaged by the notches and capable of being rocked by the notches, and a contact stud with which the arm is capable of making a number of contacts to cause the aforesaid electric impulses.

20 4. In combination with the mechanism defined in claim 2, one dialing disc being formed as an outer disc and the other dialing disc being formed as an inner disc, the outer disc having tabs numbered as tens and the inner disc having tabs numbered as units whereby after dialing the inner disc it is held in its dialed position, a clutch device holding the inner disc in its dialed position, and a ratchet and pawl device holding the outer disc from returning after dialing, and electro-magnetic means for freeing said ratchet and pawl device.

25 5. In combination with the mechanism defined in claim 2, one dialing disc being formed as an outer disc and the other dialing disc being formed as an inner disc, the outer disc having tabs numbered as tens and the inner disc having tabs numbered as units whereby after dialing the inner disc it is held in its dialed position, a clutch device holding the inner disc in its dialed position, and a ratchet and pawl device holding the outer disc from returning after dialing, and electro-magnetic means for freeing said ratchet and pawl device, means, including a knob for returning the dialing discs to bring them to their normal position after they have been dialed, a clutch freed thereby, and an electro-magnetic device to which a current is closed by the clutch to release the ratchet and pawl device.

30 6. In combination with the mechanism defined in claim 1, a screw device for moving the discs of each projector axially, a notched wheel actuating said screw device, a pawl engaged by the notched wheel to impel the notched wheel, and a solenoid moving the pawl and under the influence of electric impulses sent from the dialing apparatus.

35 7. In combination with the mechanism defined

in claim 1, a spindle affecting the rotation of the discs of each projector, a notched wheel driving the said spindle, a pawl engaging the notched wheel, and a solenoid moving the pawl to impel the notched wheel under the influence of electric impulses sent from the dialing apparatus.

8. In combination with the mechanism defined in claim 1, a spindle affecting the rotation of the discs of each projector, a notched wheel driving the said spindle, a pawl engaging the notched wheel, and a solenoid moving the pawl to impel the notched wheel under the influence of electric impulses sent from the dialing apparatus, electro-magnetic means reversing the pawls which effect the movement of the discs of each projector, and means controlling the electro-magnetic means and releasing the dialing discs to allow them to return to their normal position.

9. In combination with the mechanism defined in claim 1, means for carrying the transparencies, a set of co-axial discs in which the transparencies

are carried, each disc having one unfilled recess through which light can pass freely, one only of such discs being turned at a time, the others being locked in such positions that their open recesses lie in the line of projected light, each disc having a notch, a common locking plate adapted to be received by said notch, the locking plate having a notch which when opposite a disc which lies in the inner focal plane allows said disc

10 to be turned, the other discs remaining locked.

10. In combination with the mechanism defined in claim 1, an arbor passing axially through the dialing discs and their respective notched wheels and carrying one of the clutch parts, 15 whereby when said arbor is pressed endwise it frees said clutch, a circuit which is thereby also closed, electro-magnetic means connected with the circuit which free the one dialing disc, and electro-magnetic means which reverse the pawls 20 of each projector.

BEATRICE NORAH CARRINGTON.
